United States Patent Office.

MORRIS B. POWELL AND CHARLES W. STUTENROTH, OF NAPERVILLE,
ILLINOIS.

Design No. 3,141, dated July 28, 1868.

DESIGN FOR A BOTTLE.

The Schedule referred to in these Letters Patent and making part of the same.

TO ALL WHOM IT MAY CONCERN:

Be it known that we, MORRIS B. POWELL and CHARLES W. STUTENROTH, of the town of Naperville, county of Du Page, and State of Illinois, have originated and designed a new Pattern for Bottles, made from glass or other materials, of which the following is a full, clear, and exact description.

Our new design consists in adapting the line of beauty to any glass or other kind of bottle, combining elegance of appearance with great durability.

Claim.

What we claim as our invention, and desire to secure by Letters Patent, is—

The design for a bottle, as shown and described.

MORRIS B. POWELL,
CHARLES W. STUTENROTH.
